P. J. Simmons (Assignor of Inv. F. Rathbone)
Troy, N. Y. —

Letters Patent (Design of. 112) dated 20th March 1847.

The schedule referred to in these Letters Patent and
making part of the same.

To all whom it may concern; Be it known that I,
Peter J. Simmons of Troy, in the County of Rensselaer,
and State of New York, have invented a new ornamental de-

Dec. 112

Sign for an air-tight stone, and I do hereby declare, that the accompanying drawing is a full and accurate delineation of a Stone constructed after my said design, the sides to not王者 being similar to, and symmetrical with, those represented.

What I claim as my invention, and desire to secure by Letters Patent is, the combination and arrangement of ornamental figures and forms, represented in the accompanying drawing, marking an ornamental design for an air-tight stone.
